(57) **CLAIM**

The ornamental design for the fitness equipment, as shown and described.

DESCRIPTION

FIG. 1 is a perspective view of the fitness equipment showing my new design;

FIG. 2 is another perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of the area labeled 9 in FIG. 1;

FIG. 10 is an enlarged view of the area labeled 10 in FIG. 1;

FIG. 11 is an enlarged view of the area labeled 11 in FIG. 1;

FIG. 12 is an enlarged view of the area labeled 12 in FIG. 1;

FIG. 13 is an enlarged view of the area labeled 13 in FIG. 1;

FIG. 14 is an enlarged view of the area labeled 14 in FIG. 1;

FIG. 15 is an enlarged view of the area labeled 15 in FIG. 1;

FIG. 16 is an enlarged view of the area labeled 16 in FIG. 1;

FIG. 17 is an enlarged view of the area labeled 17 in FIG. 2;

FIG. 18 is an enlarged view of the area labeled 18 in FIG. 2;

FIG. 19 is an enlarged view of the area labeled 19 in FIG. 2;

FIG. 20 is an enlarged view of the area labeled 20 in FIG. 2; and,

FIG. 21 is an enlarged view of the area labeled 21 in FIG. 2.

(Continued)

The broken lines in the figures depict portions of the fitness equipment, that form no part of the claimed design.

1 Claim, 16 Drawing Sheets
